UNITED STATES PATENT OFFICE.

DANIEL J. McSWINEY, OF CHELSEA, MASSACHUSETTS, ASSIGNOR TO FRANCIS R. MULLIN, OF WINCHESTER, MASSACHUSETTS.

PROCESS FOR EMULSIFYING OIL OR ASPHALT.

1,384,805.

Specification of Letters Patent. Patented July 19, 1921.

Application filed March 5, 1920. Serial No. 363,458.

To all whom it may concern:

Be it known that I, DANIEL J. McSWINEY, a citizen of the United States, and resident of Chelsea, in the county of Suffolk and State 5 of Massachusetts, have invented a new and useful Process for Emulsifying Oil or Asphalt, of which the following is a specification.

The main object of my invention is to provide an emulsion which is more uniform and durable than those heretofore known and which is also cheap to manufacture.

My invention consists primarily in a continuous process for emulsifying an oil or asphalt or similar material and in the preferred form it consists in the conduction or passage of an emulsifying material, such as soap or soap solution through a suitable container and the gradual addition to the emulsifying material of the material to be emulsified while the former is passing through the container. I also prefer to have said addition uniform as well as gradual and to provide that at no place during said passage 25 shall the volume of the material to be emulsified amount to more than four times the volume of the material which is to accomplish the emulsification.

A feature is a machine for carrying out 30 said process, primarily including mechanism which not only conveys the material through the container but also and at the same time thoroughly mixes the ingredients.

Other features will be pointed out below.

In the drawing—

Figure 1 is an elevation, partly in section,

of a machine for carrying out my process: Fig. 2 is a section on line 2—2 of Fig. 1; and

Fig. 3 is a section on line 3—3 of Fig. 1.

In my process the soap or soap solution or similar material is fed in at one end of the container and an amount of oil less than 4 times its volume is added to it. The oil and soap are mixed thoroughly by a mixing arrangement in the container, and while being mixed they are conducted away from the end of the container to another point where more oil is being fed into the container. Before, 45 however, the oil and soap reach this second point they should be so thoroughly mixed that the oil that has been first added to the soap is changed to an emulsified condition. At the second point a quantity of oil approxi-

50 mately equal to that first added is added to

the mixture of oil and soap, and the whole is again so thoroughly mixed that the second addition of oil is changed to an emulsified condition and in the meanwhile the whole is conducted to a third point where oil is being 60 fed into the container, and here the same process is repeated. This process is repeated until there has been added to the soap, as great an amount of oil or asphalt as it will emulsify. The addition of water is then a 65 simple matter and can be carried out in a way similar to that in which the addition of oil is carried out, that is to say, the emulsion may be passed through a similar container and water gradually added in a way similar 70 to that described for the addition of the oil.

It can be readily seen that the mechanical arrangement for carrying out this process may take many forms. The container used may consist of a cylinder or of a series of 75 cylinders in communication with each other, or it may be conical in shape. If cylinders be used they may be worked in a vertical, horizontal or inclined position.

The addition of oil to the mixer or container may be continuous, semicontinuous or discontinuous. The addition of oil may be made continuous by feeding the oil to the container through a slit in the side of the container running in the direction of flow of 85 the soap and oil mixture in the container. The oil may be fed through the slit from a reservoir connected to the container throughout its length. In order that the feeding of the oil through the slit into the container 90 may be uniform, the slit can be made to increase in width as it becomes more distant from the point at which the oil or asphalt is fed into the reservoir. This method of feeding the oil or asphalt into the container will 95 give very good results. It will probably give a more perfect emulsion and one with a lower soap content than can be obtained by any other process of direct manufacture, but this method of feeding the oil is rather difficult to control. Moreover the emulsion obtained in this way is often too perfect. A scientifically perfect emulsion is not, usually, as good for road work as one which is only partially perfect. This latter objection may be largely overcome by using only a short slit, but this does not allow the degree of control that can be obtained by other methods of feeding.

The feeding of the oil may be made semi-

continuous by feeding through two or more slits into the container. This allows of more control than does the preceding method of feeding.

- 5 The feeding of the oil may be made discontinuous by feeding the oil into the mixer through several points along the length of the container and this is the method I prefer. This method of feeding allows of the 10 greatest amount of control. In order to work most efficiently it is necessary first that the separate additions be approximately equal in volume *i. e.*, that no addition of oil be more than twice the volume of any other 15 addition of oil; second, that the oil be added in at least five separate additions; and third that the amount of oil in each addition be not more than 4 times the volume of soap or soap and oil mixture to which it be added. 20 In order that the first requirement be met, I will use the feeding arrangement shown in the drawing which I have found to give very good results. The only difference in amount of oil fed into the separate pipes, 25 if each pipe has the same diameter, is occasioned by difference in length of pipe or in presence of bends, etc., and this difference can be very easily controlled. It is inad- 30 visable to feed the oil into a pipe running the length of the mixer, and from which side pipes lead into the mixer, for in such a case the side pipe nearest the feed will receive very much more than the other side pipes, and the other side pipes after the 35 third or fourth nearest the feed will receive but very little oil. The amount of oil added to the mixer will be 25-35 times the amount of soap added. If the amount of oil added to the soap or to a soap and 40 oil mixture be 4 times the amount of the soap or soap and oil mixture it will be very difficult to emulsify the oil. If then the oil be added to the container in less than five separate additions some of these addi- 45 tions will amount to more than 4 times the soap or soap and oil mixture to which they are added.

The most critical point in the manufacture of an emulsion is the beginning of the 50 emulsification. The amount of oil added to the soap for the beginning of the emulsion should never be more than 4 times the amount of the soap. In the same manner the separate feeds should preferably be at 55 such a distance from each other that the oil fed at one point will be emulsified before reaching the next feeding point. For example, suppose a gallon of soap or of soap and oil mixture passes through the container. 60 It reaches a point where oil is being fed into the container and requires some time to be conducted past this point. In the time required for this gallon of soap or soap and oil mixture to pass this point the amount of 65 oil fed to it at this point should not be more

than 4 times its volume *i. e.*, in this case the amount of oil fed into the container at this point during the time it takes for the gallon of soap or of soap and oil mixture to pass this point should not be more than 4 70 gallons. Moreover, before this gallon of soap or soap and oil mixture reaches the next point at which oil is being fed into the container, the oil fed at the first point should be thoroughly mixed and emulsified. This 75 is especially true if the oil is being added to the container in only a small number of additions. I have found that if the oil be added uniformly to the container and in more than ten separate additions the amount 80 of soap required may be materially reduced.

The oil is usually fed into the container through the wall of the container, but it may, instead, be fed into the container through the mixing shaft, or through the 85 mixing arrangement.

I have found that a very efficient mixing and emulsification can be obtained by using a series of metal strips, running in the direction of the flow of the material in the 90 container and attached to metal rods connected to the mixing shaft.

The mixing arrangement preferably serves as the means of conveying the soap or the soap and oil mixture through the mixer 95 from one point of feed to the next. This result can be obtained by having the rubbing surface of the strips or other mixing arrangement revolve in a direction not perpendicular to the surface of the mixing 100 arrangement but at an acute angle to it, *i. e.*, so that the part of the strip or other mixing arrangement nearest the end of the mixer at which the soap enters will revolve ahead of that part of the mixing arrangement 105 nearest the point at which the emulsion leaves the mixer.

A pump should preferably not be used for the purpose of conducting or forcing the soap or the soap and oil mixture through 110 the container from one point of feed to the next. The function of the pump is simply to supply to the mixer soap or soap solution and oil or asphalt, in a definite ratio. In an emulsion to be used for road work, the 115 soap or soap solution is always the dispersion means and the oil or asphalt is the dispersed phase. The ratio of dry soap to oil or asphalt in the emulsion as ordinarily made is about 1:30 or 1:35. Emulsions are 120 always unstable systems, but they are especially unstable when the ratio between dispersion means and dispersed phase is as low as it is in this case. If this ratio of soap to oil or asphalt be increased the cost of the 125 emulsion increases and its quality decreases; for the soap is the most expensive material used in the emulsion, and the more soap the emulsion contains the less value it has for paving purposes. If this ratio of soap to 130

oil or asphalt be decreased the emulsion will, in most cases, separate, become worthless and have to be worked over again.

From this it is evident that a definite ratio 5 of supply of soap and oil or asphalt to the container should be maintained. The pumps supplying the soap and oil or asphalt to the container should be geared together and run so as to deliver to the container, soap and 10 oil or asphalt in the ratio desired. Moreover, any condition that tends to interfere with the action of the pumps in delivering the soap and oil or asphalt in the desired ratio should be avoided. The condition 15 most likely to interfere with this operation is a back pressure exerted on the pumps from some condition existing in the mixer or in the connections between the pumps and the mixer. A back pressure will be exerted on 20 the pumps, if the pumps be relied upon to force the soap and oil mixture through the container. Moreover, this back pressure will not be a constant one. During the process of emulsification the soap and oil mixture 25 changes from a comparatively thin fluid to a condition that is often practically that of a stiff solid. The stiffness obtained by the mixture will depend upon the character of the oil, the temperature of the oil and soap, 30 the character of the soap, the rate at which the oil is fed into the mixture and the rate at which the oil and soap is mixed, etc. The back pressure exerted on the pumps will vary according to the degree of stiffness obtained by the mixture during the process of 35 emulsification. The back pressure will be exerted on both the oil and the soap pumps, but its effect will be felt more on the soap pump which is usually by far the smaller of 40 the two, and here its action will be the most disadvantageous for only a slight difference in the pumping of the soap will usually make a great difference in the emulsification.

A back pressure on the pumps may also 45 be caused by having the actuating surfaces of the mixing arrangement so revolve as to throw the mixture outward toward the wall of the container and the points of feed of the oil into the container. To avoid this it 50 is desirable that the rubbing surface of the mixing arrangement *i. e.* the surface opposed to the mixture during the revolution of the mixing arrangement should be so arranged as to throw the mixture inward during revolu- 55 tion.

It is not necessary that the container be kept full during the operation of the process, so long as the soap and oil are being fed into the mixer in a constant ratio. In most 60 cases, however, it is desirable that the container be kept substantially full in order that the finished emulsion may be uniform in quality. This result can be obtained by having the outlet from the container at the 65 highest point of the container, by having

the outlet pipe leave from the top of the container, by having the outlet pipe so arranged that part of it is higher than the top of the container, by having the container in an inclined position so that the exit end be higher 70 than the entrance end, or by placing within the container, overflow partitions, with the openings near the top of the container, and over which the emulsion must pass before leaving the container, the last being the 75 method I prefer.

It is evident that as the soap and oil mixture passes through the container, it constantly increases in volume, so that the amount of material leaving the mixer will 80 amount to 20 to 30 times the amount of soap entering the mixer at the other end. Accordingly if the mixer be of uniform size throughout its length, the material within it will be moving or should be moving 85 30 times as fast at one end of the mixer as it is at the other end. In order to attain the same rate of speed of the material throughout the mixer, a conical mixer might be used. A similar result can be obtained by 90 having the mixer made up of sections of pipe of gradually increasing diameter by using a series of separate containers each of which is larger than the preceding one as explained below, or by having the conveying 95 arrangement so made as to convey at a speed in converse ratio to the volume of material. In a mixer of uniform size throughout this difference might be avoided by having the conveying arrangement so constructed as to 100 convey at a speed in inverse proportion to the volume of the material and to have the distance between the points of feed of the oil into the mixer so increase that the oil fed at one point would be completely emulsified 105 before the next point was reached.

For, then, the most successful and efficient operation of the process, the soap should be fed in at one end of the mixer and conducted through the mixer while the oil 110 should be fed gradually to the soap as it passes through the mixer, the whole being stirred and mixed thoroughly during the operation. The addition of the oil to the soap should be preferably made gradually 115 and uniformly. If the addition of the oil be discontinuous the addition of 20 or more parts of oil to one part of dry soap should take place in at least five separate additions, and no one of these additions should 120 amount to more than four times the volume of the material to which it be added, *i. e.* the amount of oil passed through one point of feed into the mixer during a unit length of time should have a volume less than four 125 times the volume of the soap or the soap and oil mixture that passes that point during the same unit of time; moreover, that the rate of conduction of the material through the mixer, the spacing of the points 130

through which the oil is added, and the rate and manner of the mixing of the material should preferably be such that as the material comes to a point in the mixer where the 5 oil is being fed into the mixer, this material should contain no unmixed or unemulsified oil which was fed to it at some previous point. The function of the pumps should be merely to feed oil and soap into the mixer 10 in a definite and constant ratio. The conduction of the material through the mixer and the mixing of this material should preferably be so arranged as to exert no back pressure on the pumps. It is not necessary 15 that the container be kept full during the process of emulsification; in order, however, that the most efficient operation be attained it is advisable that this be done. The addition of water to the emulsion of soap 20 and oil in order to dilute it, can be brought about in an apparatus and in a manner similar to those used for the emulsification.

The type of mixer I prefer to use in carrying out my process consists of a series of 25 seven cylindrical metal containers, each being in communication with the next in the series. I have thought it unnecessary to illustrate in the drawing all these containers. The oil or asphalt supply pipe A may 30 be controlled by a suitable pump (not shown) and leading from said pipe is an overflow pipe A', pipe A leading to the main oil or asphalt reservoir B, from which lead the main oil or asphalt feed pipes b b' 35 b², b³ and b⁴, each leading to one of the first five of the seven containers above referred to. The feed pipe b, for example, is controlled by valve b⁵ and has branches b⁶ and b⁷, one leading to the oil or asphalt reservoir D and the other to reservoir D', small asphalt feed pipes d leading from reservoir D to the container E and small oil or asphalt feed pipes d' leading from reservoir D' to said container. The first five 40 containers are of progressively increasing diameter to take care of the increasing volume of the material, are connected by pipes b b', b², b³, b⁴ with main reservoir B' and are for the emulsification of the soap and oil, 45 while the last two of the seven above referred to are for the addition of water to the emulsion. The containers are preferably in a horizontal position, the soap or soap solution being fed in by pipe F controlled by pump F'. Each container of the seven, of which I illustrate one, has a rotary shaft E' to which are rigidly connected a series of radial arms e e' e² e³ and e⁴ and another series e⁵ e⁶ e⁷ e⁸ and e⁹, each of said 50 arms extending radially nearly to the wall of the container, arm e being diametrically opposite arm e⁵ and so on with the other arms. A metal strip g, beveled as shown, is fastened to the outer end of arms e to e⁴ 55 and a similar strip g' to the outer end of

arms e⁵ to e⁹. A similar strip g² is fastened to arms e to e⁴ a little nearer to the shaft and a similar strip g³ is fastened to arms e⁵ to e⁹. Similar strips g⁴ and g⁵ are also attached to arms e to e⁴ and other similar 70 strips g⁶ and g⁷ are attached to arms e⁵ to e⁹. In Figs. 1 and 3 I show only strips g and g' because the showing of the other strips might confuse the showing in those figures. 75

Near the end of each container I provide a fixed overflow partition H to keep the container substantially full, this partition being circular and fitting the wall of the container but not extending to the top thereof, leaving a passage at h for the material to reach the outlet H' leading to the next container which is supplied by pipe b', the pipes b to b⁴ feeding a substantially uniform amount of oil or asphalt to the several containers. The size of the passage h 85 may be varied by using different sizes of partitions.

The shaft E' may be rotated by any suitable gearing and in order that the strips 90 may act not only as mixers, but also, and simultaneously, as conveyors of the material through the container, they are helical and are revolved so that the parts of the strips nearest the inlet F precede in revolution the parts nearest the partition. 95

At the same time, the surface of the metal strips opposed to the mixture during revolution is not parallel to an axis of the revolving shaft but at an angle to it, so that 100 the mixture is thrown inward during the revolution of the shaft.

As, in order that the material in the mixer be mixed quickly and thoroughly, the shaft will be revolved at a rather high 105 speed, it is well that the mixing strips in running from one end of the container to the other do not turn through too great an angle, otherwise the material will be conducted too rapidly through the mixer. A 110 turn of the strips through about 90 degrees will be sufficient.

A great advantage of my continuous process as compared, for example, with a batch process, is that the product is much 115 more durable and uniform.

Another advantage is that the mixing is very efficiently done, particularly because of the reasons already given and also because the spacing of the strips permits a great 120 amount of rubbing of the ingredients one upon the other and also rubbing on the surfaces of the strips themselves.

What I claim is:

1. The process of emulsification consisting in passing emulsifying material through a container and gradually adding to it the material to be emulsified, said addition being such that at no place during said passage shall the volume of material to be 125 130

emulsified amount to more than four times the volume of the emulsifying material.

2. The process of emulsification consisting in passing emulsifying material through a container continuously, and gradually adding to it the material to be emulsified, said addition being such that at no place during said passage shall the volume of material to be emulsified amount to more than four times the volume of the emulsifying material.

3. The process of emulsification consisting in passing through a container saponaceous material having sufficient water to enable it to act as an emulsifying agent and gradually adding to it bituminous material, said addition being such that at no place during said passage shall the volume of unmixed or unemulsified bituminous material amount to more than four times the volume of the saponaceous material.

4. The process of emulsification consisting in passing continuously through a container saponaceous material having sufficient water to enable it to act as an emulsifying agent and gradually adding to it bituminous material, said addition being such that at no place during said passage shall the volume of unmixed or unemulsified bituminous material amount to more than four times the volume of the saponaceous material.

5. The process of emulsification consisting in feeding to a container saponaceous material having sufficient water to enable it to act as an emulsifying agent and adding to it an amount of bituminous material less than four times the volume of the saponaceous material, then passing the materials along in the container to another point, mixing them during said passing until the bituminous material is changed to an emulsified condition, then at said point adding to the mixture a quantity of bituminous material approximately equal to the quantity first added, then passing the materials along in the container to another point, mixing them during the last-mentioned passing until the bituminous material is changed to an emulsified condition and repeating until there has been added to the saponaceous material as great an amount of bituminous material as it will emulsify.

6. The process of emulsification consisting in feeding to a container saponaceous material having sufficient water to enable it to act as an emulsifying agent and adding an amount of bituminous material less than four times the volume of the saponaceous material, then passing the materials along in the container to another point, mixing them during said passing until the bituminous material is changed to an emulsified condition, then at said point adding to the mixture a quantity of bituminous

material approximately equal to the quantity first added, then passing the materials along in the container to another point, mixing them during the last-mentioned passing until the bituminous material is changed to an emulsified condition and repeating until there has been added to the saponaceous material as great an amount of bituminous material as it will emulsify and then passing the material through another container and gradually adding water during the last-mentioned passing.

7. The process of emulsification consisting in passing through a container saponaceous material having sufficient water to enable it to act as an emulsifying agent and adding bituminous material in at least five separate additions, substantially equal in volume, each addition being not more than four times the volume of the saponaceous material or of the saponaceous and bituminous mixture to which it is added, and mixing the materials during said passing.

8. The process of emulsification consisting in feeding continuously to a container saponaceous material having sufficient water to enable it to act as an emulsifying agent and adding to it an amount of bituminous material less than four times the volume of the saponaceous material, then passing the materials along in the container to another point, mixing them during said passing until the bituminous material is changed to an emulsified condition, then at said point adding to the mixture a quantity of bituminous material approximately equal to the quantity first added, then passing the materials along in the container to another point, mixing them during the last-mentioned passing until the bituminous material is changed to an emulsified condition and repeating until there has been added to the saponaceous material as great an amount of bituminous material as it will emulsify.

9. The process of emulsification consisting in feeding continuously to a container saponaceous material having sufficient water to enable it to act as an emulsifying agent and adding an amount of bituminous material less than four times the volume of the saponaceous material, then passing the materials along in the container to another point, mixing them during said passing until the bituminous material is changed to an emulsified condition, then at said point adding to the mixture a quantity of bituminous material approximately equal to the quantity first added, then passing the materials along in the container to another point, mixing them during the last-mentioned passing until the bituminous material is changed to an emulsified condition and repeating until there has been added to the saponaceous material as great an amount of bituminous ma-

terial as it will emulsify and then passing the material through another container and gradually adding water during the last-mentioned passing.

5 10. The process of emulsification consisting in passing continuously through a container saponaceous material having sufficient water to enable it to act as an emulsifying agent and adding bituminous material in at least five separate additions, substantially equal in volume, and mixing the materials during said passing.

10 15. The process of emulsification consisting in passing continuously through a container saponaceous material having sufficient water to enable it to act as an emulsifying agent and adding bituminous material in at least five separate additions, substantially equal in volume, each addition being not more than four times the volume of the saponaceous material or of the saponaceous and bituminous mixture to which it is added, and mixing the materials during said passing.

11. The process of emulsification of bituminous material consisting in feeding to a container saponaceous material having sufficient water to enable it to act as an emulsifying agent and adding to it a portion of the bituminous material, then passing the materials along in the container to another point, mixing them during said passage until the bituminous material is changed to an emulsified condition, then at said point adding another portion of the bituminous material, then passing the materials along in the container to another point mixing them during said passage until the bituminous material is changed to an emulsified condition and repeating until there has been added to the saponaceous material as great an amount of bituminous material as it will emulsify.

12. The process of emulsification of bituminous material consisting in feeding to a container saponaceous material having sufficient water to enable it to act as an emulsifying agent and adding to it a portion of the bituminous material, then passing the material along in the container to another point, mixing them during said passage until the bituminous material is changed to an emulsified condition, then at said point adding another portion of the bituminous material, then passing the materials along in the container to another point mixing them during said passage until the bituminous material is changed to an emulsified condition and repeating until there has been added to the saponaceous material as great an amount of bituminous material as it will emulsify, and then passing the material through another container and gradually adding water during the last-mentioned passing.

13. The process of emulsification consisting

in passing through a container saponaceous material having sufficient water to enable it to act as an emulsifying agent and adding bituminous material in at least five separate additions, substantially equal in volume, and mixing the materials during said passing.

14. The process of emulsification of bituminous material consisting in continuously feeding to a container saponaceous material having sufficient water to enable it to act as an emulsifying agent and adding to it a portion of the bituminous material, then passing the materials along in the container to another point, mixing them during said passage until the bituminous material is changed to an emulsified condition, then at said point adding another portion of the bituminous material, then passing the material along in the container to another point mixing them during said passage until the bituminous material is changed to an emulsified condition and repeating until there has been added to the saponaceous material as great an amount of bituminous material as it will emulsify.

15. The process of emulsification of bituminous material consisting in feeding continuously to a container saponaceous material having sufficient water to enable it to act as an emulsifying agent and adding to it a portion of the bituminous material, then passing the materials along in the container to another point, mixing them during said passage until the bituminous material is changed to an emulsified condition, then at said point adding another portion of the bituminous material, then passing the materials along in the container to another point mixing them during said passage until the bituminous material is changed to an emulsified condition, then at said point adding another portion of the bituminous material, then passing the materials along in the container to another point mixing them during said passage until the bituminous material is changed to an emulsified condition and repeating until there has been added to the saponaceous material as great an amount of bituminous material as it will emulsify and then passing the material through another container and gradually adding water during the last-mentioned passing.

16. The process of emulsification consisting in passing continuously through a container saponaceous material having sufficient water to enable it to act as an emulsifying agent and adding bituminous material in at least five separate additions, substantially equal in volumes, and mixing the materials during said passing.

DANIEL J. McSWINEY.
